(57) **CLAIM**

The ornamental design for a microscope stand, as shown and described.

DESCRIPTION

This application contains subject matter related to the following co-pending U.S. design patent applications:

Application Ser. No. 29/542,684, filed herewith and entitled "Microscope"; and

Application Ser. No. 29/542,687, filed herewith and entitled "Stand and Pivot Unit".

FIG. 1 is a rear view of a microscope stand according to the design;

FIG. 2 is a right side view thereof;

FIG. 3 is a front view thereof;

FIG. 4 is a left side view thereof;

FIG. 5 is a front, left perspective view thereof;

FIG. 6 is a top view thereof; and,

FIG. 7 is a bottom view thereof.

The broken lines are for illustrative purposes only and form no part of the claimed design.
